UNITED STATES PATENT OFFICE.

CHESTER S. JENNINGS, OF BOSTON, MASSACHUSETTS, ASSIGNOR TO THE LAMSON COMPANY, (FORMERLY LAMSON CONSOLIDATED STORE SERVICE COMPANY,) OF BOSTON, MASSACHUSETTS, A CORPORATION OF NEW JERSEY.

ELECTRIC-MOTOR CONTROL.

1,137,006.

Specification of Letters Patent. Patented Apr. 27, 1915.

Application filed June 17, 1911. Serial No. 633,648

To all whom it may concern:

Be it known that I, CHESTER S. JENNINGS, of Boston, in the county of Suffolk and State of Massachusetts, have invented certain new and useful Improvements in Electric-Motor Control; of which the following is a specification.

My invention consists of a control for an electric motor when used to operate a pump or exhauster for generating fluid pressure for transmitting carriers, or substance through a pneumatic tube system reliably and in a predetermined time, the primary actuating means being located at a distance from the said control. The functions to be performed by this control are to start the motor and by suitable means connecting it with a pump, or exhauster to begin to generate a fluid force and continue in operation the production of this force a predetermined time, sufficient to effect the transmission of a carrier or the proper quantity of a substance, to reset the timing mechanism so that the duration of the operation will be exactly the same if a secondary effect is exacted during the interval of the initial timing or any subsequent interval of timing and finally to cause the motor to stop and arrest the generation of the fluid force.

Another object of my invention is to provide a control for an electric motor when used to drive a pump or exhauster operatively connected to a pneumatic tube transmission system that will permit of the motor being started from a distant point, timing its duration of operation uniformly even if the primary actuating contact be rapidly made and broken. In other words, if the duration of the primary actuating contact be less than the time required to energize the timing solenoid and thereby cause its armature to fail to complete its full movement, means is provided to effect the full movement of the armature independent of the primary actuating contact, thus causing motor to operate for the time predetermined.

Like letters of reference refer to like parts throughout the several views.

In the drawings Figure 1 represents a plan view of a panel on which the controlling mechanism is mounted showing the necessary wiring connections. Fig. 2 is a vertical detail section taken on line II-II of Fig. 1.

P is a primary actuating solenoid whose leads are P⁸ and P⁹ and whose armature P' carries the contact plates P² and P³ insulated from each other and from the armature P', contact plate P² being adapted to engage contact posts P⁴ and P⁵ and contact plate P³ to engage contact post P⁶ and P⁷.

T is a timing solenoid the leads of which are T¹ and T² and whose armature is T³ and which carries the flexibly mounted contact plate T⁴ which is insulated from the armature and is elastically held against the flange T⁵ which is affixed to the armature T³ and which is adapted to come in contact with the contact posts E and E' when the armature is attracted upward. Affixed to the armature T³ is a member T⁶ projecting inward and upward toward the panel and adapted to engage the switch arm X^a and open the circuit closed by the switch X which completes a circuit between the contact posts X' and X². Carried on the upper end of the armature T³ is the timing cylinder D in which is fitted a piston D' attached to the piston rod D² which is affixed to the pivot D³ mounted on the panel. The lower main or lower portion of the piston rod D² is tubular and contains a metal ball D⁵ adapted to close the opening in the lower end of said rod, the lower end of the tubular opening of the piston rod D' being contracted to form a seat for this ball valve. A small hole D⁶ connecting the tubular portion of the piston rod D² with the space above the piston D', and a hole D⁷ in the rod D² completes a passage (controlled by the ball valve) between the space above and below the piston; thus permitting the cylinder D carried on the armature T³ of the

solenoid T to ascend without resistance when the solenoid is energized.

D⁴ is a screw adapted to control a vent D⁸ in the lower portion of the cylinder D so as to control its descent.

S is a motor starting solenoid whose leads are S' and S² and whose armature S³ carries the laminated lower contact S⁴ which is adapted, when carried upward by the energization of solenoid S to close the motor circuit through the contacts S⁵ and S⁶.

M and M' are the high potential mains or leads and C is a battery, dynamo, or other source of current of low voltage for the push button circuit. This button or circuit maker has been designated A², and when actuated completes the following circuit: From battery C current flows over wire A to solenoid P, thence back over wire B to the push button A² and from thence via wires P^{2a} and P^a back to the battery. The armature P' of the energized solenoid P carries its contact plates P² and P³ up into contact with posts P⁴, P⁵, P⁶ and P⁷, completing the following circuit: From battery C via wire A, solenoid P, wire B to wire Q, post P⁵, plate P², post P⁸, wire P¹⁰, switch arm X^a, switch contacts X and X', wires P^{3a} and P^a back to battery. This constitutes a maintaining circuit for solenoid P when the push button is released and hence plates P² and P³ remain in contact with their respective posts, which assures the complete upward movement of the armature T³ of the solenoid T, the latter being energized by the following circuit: Lead M¹ from a high potential generator, fuse R¹, wire R², main line switch G, wires M⁴ and R⁴ to solenoid post T², thence via solenoid T to post T¹, wire M³, post P⁷, plate P⁸, post P⁶, wire M², main line switch G, wire R⁵, fuse R⁶ and lead M back to the generator. The upward movement of the armature T³ of the energized solenoid T brings its yieldingly mounted contact plate T⁴ into engagement with contact posts E and E' and completes a circuit through the motor-starting solenoid S as follows:—Lead M¹ from the generator, fuse R¹, switch G, wire M⁴, wire V, post E', plate T⁴, post E, wire M⁵, post S¹, solenoid S, post S², wire M², switch G, wire R⁵, fuse R⁶, lead M, back to the generator. Plate T⁴ and solenoid S are hence in parallel with plate P⁸ and solenoid T. The armature S³ of the energized solenoid S, rises until its laminated contact S⁴ closes the gap in the motor circuit between contact posts S⁵ and S⁶, current flowing at such time from generator lead M¹, through R¹, R², switch G, M⁴, motor lead M⁷, or motor M⁶, lead M⁸, post S⁶, contact S⁴, post S⁵, wire M², switch G, R⁵, R⁶, to generator main M, causing the motor to operate. The armature T³ has af-

fixed to it a member T⁶ which continues to rise with the armature after plate T⁴ has engaged its contacts, compressing spring T⁷, and engaging and lifting the arm X^a of the switch X in the maintaining circuit. This breaks the circuit and thereby deenergizes solenoid P, the armature P' of which, carrying the contact plates P² and P³, drops opening the circuit which energizes the solenoid T and the maintaining circuit which has already been opened by the switch X. The solenoid T now being deenergized permits its armature T³ which carries the timing cylinder D to descend at a speed which is predetermined by the admission of air to the cylinder D through the orifice controlled by the timing screw D⁴. As the member T⁶ descends the lever T⁸ is lowered, permitting the switch X to reengage its contact X' thus closing the maintaining circuit at this point, but, as has already been shown, this maintaining circuit has previously been broken at contact posts P⁴ and P⁵ owing to the descent of the armature P' so that the solenoid T will not be reenergized unless the primary or push button circuit is again closed. If, however, the push button or primary circuit is not closed and the armature T³ is allowed to complete its descent, the motor will be stopped owing to the circuit which maintains energized the motor starting solenoid S being broken when the contact plate T⁴ is forced out of engagement with contact posts E and E' by the flange T⁵. It will readily be seen that if the push button circuit was closed prior to the complete descent of the armature T³ a complete cycle of the timing operation would nevertheless take place the only feature not affected being the upward movement of the armature of the motor solenoid S³ which would already be in its uppermost position. In other words, the mechanism is adapted to be retimed without interfering with the motor circuit.

Having thus described my invention, what I claim, and desire to secure by Letters Patent of the United States is:

1. In a control for an electric motor, electrically actuated means for starting the motor from a distant point, means unaffected by the power generated by the motor for timing the duration of the operation of the motor when started, said timing means adapted to be re-set to extend the operation of said motor uninterruptedly at any time during the period of operation of the same and means for insuring a setting of said timing means to time for a full period whenever said first mentioned means is actuated.

2. In a control for an electric motor, electrically actuated means for starting the motor from a distant point, pneumatic means unaffected by the power generated by the

- motor for timing the duration of the operation of the motor when started, said timing means adapted to be re-set to extend the operation of said motor uninterruptedly at any time during the period of operation of the same and means for insuring a setting of said timing means to time for a full period whenever said first mentioned means is actuated.
- 10 3. In a control for an electric motor, a controlling circuit having provisions for temporarily establishing motor-starting current conditions therein and separate provisions for maintaining said conditions when established, means controlled by said circuit for enabling the operation of said motor by electric current only so long as said conditions remain established, and means, operating independently of the power generated by said motor, for timing the duration of said conditions whereby to automatically limit the operation of said motor.
4. In combination, an electric motor having a circuit, a controlling circuit independent of the motor circuit and operating at a lower potential than said motor, said controlling circuit having provisions for temporarily establishing motor-starting current conditions therein and separate provisions for maintaining said conditions when established, means, controlled by said controlling circuit and including an electro-magnetic device operating at a higher potential than said circuit, for disestablishing said conditions while enabling the operation of said motor by electric current for a determined period running from the disestablishment of said conditions, and means for timing the duration of said period whereby to automatically limit the operation of said motor.
5. In a control for an electric motor, a motor controlling circuit including an electro-magnetic device having a part movable into and out of a position in which it is adapted to render the motor operative, provisions for maintaining said part in its motor operating position when once disposed therein, a second electric circuit dominated by said device and including a second electro-magnetic motor-controlling device, means controlled by said second device for rendering the provisions aforesaid inoperative, and means, controlled by one of the devices aforesaid, for insuring that said motor shall continue to operate for a determined period of time subsequent to the rendering inoperative of said provisions.
6. In a control for an electric motor, a motor controlling circuit including an electro-magnetic device having a part movable into and out of a position in which it is adapted to render the motor operative, provisions for maintaining said part in its motor operating position when once disposed therein, and means for timing a movement of said second device to normally limit the operation of said motor to a period determined by said timing means.
7. In a control for an electric motor, a motor controlling circuit including an electro-magnetic device having a part movable into and out of a position in which it is adapted to render the motor operative, provisions for maintaining said part in its motor operating position when once disposed therein, a second electric circuit dominated by said device and including a second electro-magnetic motor-controlling device, means controlled by said second device for rendering the provisions aforesaid inoperative only after a part of said second device has been moved a determined distance, said part having a tendency for a second determined movement thereafter, means to time said second movement, and a motor-starting-switch controlled by one of the devices aforesaid.
8. In a control for an electric motor, a motor controlling circuit including an electro-magnetic device having a part movable into and out of a position in which it is adapted to render the motor operative, provisions for maintaining said part in its motor operating position when once disposed therein, a second electric circuit dominated by said device and including a second electro-magnetic motor-controlling device, means, controlled by said second device for rendering the provisions aforesaid inoperative, means for timing a movement of said second device, and an electrically operated motor-starting switch having a circuit directly controlled by said second device.
9. In a control for an electric motor, a motor controlling circuit including an electro-magnetic device having a part movable into and out of a position in which it is adapted to render the motor operative, provisions for maintaining said part in its motor operating position when once disposed therein, a second electric circuit dominated by said device and including a second electro-magnetic motor controlling device, means controlled by said second device for rendering the provisions aforesaid inoperative, and means, controlled by one of the devices aforesaid, for insuring that said motor shall continue to operate for a determined period of time subsequent to the rendering inoperative of said provisions.
- 10 11. In a control for an electric motor, a controlling circuit, independent of the motor circuit, having means for temporarily establishing motor-starting current conditions therein and separate provisions for maintaining said conditions, when established, independently of a re-operation of said means, means, controlled by said controlling circuit for enabling the operation of said motor by electric current for a determined period longer than that during which said conditions remain established, and means for timing the duration of said period whereby to normally limit the operation of said motor, said timing means adapted to be retimed at any time during said period by a re-actuation of said first mentioned means, so that the motor will invariably be operated.

for the full period after every actuation of said condition establishing means.

10. In a control for an electric motor, a primary controlling circuit including an electro-magnetic device and having provisions for maintaining said device operative when once energized, a secondary electric circuit dominated by said device and including a second electro-magnetic device, 10 said secondary electric circuit having two branches in one of which is said second device and in the other of which is an electrically operated motor-controlling switch, and

means for automatically deenergizing the second of said devices after the lapse of a 15 determined interval subsequent to the energization thereof.

In testimony whereof, I have signed my name to this specification in the presence of two subscribing witnesses this 9th day of 20 June, A. D. 1911.

CHESTER S. JENNINGS.
